F. NAGLER

ROTOR

Filed June 7, 1922

UNITED STATES PATENT OFFICE.

FORREST NAGLER, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

ROTOR.

Application filed June 7, 1922. Serial No. 566,517.

To all whom it may concern:

Be it known that FORREST NAGLER, a citizen of the United States, residing at Wauwatosa, in the county of Milwaukee and 5 State of Wisconsin, has invented a certain new and useful Improvement in Rotors, of which the following is a specification.

This invention relates in general to improvements in the art of converting hydraulic energy into commercial power appearing as torque in a rotating shaft, and relates more specifically to improvements in the construction and operation of hydraulic turbine rotors and the like.

10 15 An object of the invention is to provide a hydraulic turbine rotor which is simple in construction and efficient in operation. Another object of the invention is to provide a hydraulic turbine rotor which is capable 20 of producing relatively high specific speed and which is further capable of converting maximum hydraulic energy into commercial power when operating under relatively low head. A further object of the invention is 25 to provide improvements in vane structures, which are generally applicable to rotors of hydraulic machines.

As illustrated in a number of publications including an article published in volume 41, 30 No. 18 of Mechanical Engineering, it has heretofore been proposed to provide a hydraulic turbine rotor consisting of a series of dove-tail shaped non-overlapping vanes radiating from a central hub and having 35 free outer extremities. In constructing the early rotors of this general type, attention was especially directed to proper formation of surfaces of the rotor vanes which were subject to direct pressure, the vanes being 40 formed of such thickness only as would facilitate manufacture and would enable them to safely resist destructive forces such as the rotor propelling pressures acting 45 against the vane surfaces and centrifugal forces set up in the rotor during operation. The vanes resulting from proper consideration of these factors, while producing relatively satisfactory specific speeds and efficiencies were comparatively thin and did 50 not produce proper operating conditions in the rotor.

It has been discovered that by thickening the rotor vanes and by properly forming the leading edges and faces of the thickened

vanes, the efficiencies of such rotors may be 55 considerably increased without materially affecting the attainable specific speeds. The improved rotor vanes are preferably thickened along the outer portions of their advancing edges and are curved along their 60 advancing surfaces. By thus constructing the rotor vanes it is possible to secure a maximum reduction in pressure along the leading surfaces of the rapidly advancing 65 vanes during operation of the rotor. It is 70 a well known fact that this type of low head high speed hydraulic turbine is operable by pressure exerted by the whirling stream of water against the trailing surfaces of the 75 rotor vanes and by a suction or under-pressure 80 created along the leading surfaces of the rapidly advancing vanes. By properly curving these leading surfaces and disposing 85 these surfaces at steep angles relatively to the plane of rotation, the pressure tending to retard advancement of the vanes is 90 reduced to a minimum. The thickening of the vanes relatively near to their leading or advancing edges, also eliminates shock of entry of the water thereby avoiding eddy 95 losses such as result with vanes having relatively thin advancing edges. It will be obvious that the improved results may be attained by utilizing hollow as well as solid 100 vanes, but the additional flywheel effect attainable by the use of relatively heavy solid vanes is an advantage rather than a detriment. This improved construction of rotor vanes forms part of the subject of the present invention and is applicable generally to 105 various types of rotors for hydraulic machines.

Another object of the present invention is to provide other improvements in the construction of hydraulic rotor vanes of the high speed low head type wherein the degree of energy conversion is dependent largely upon the quantity of water passed through the rotor and upon the proper shape and distribution of the vane surfaces, rather than upon the pressure of the entering water. In one embodiment of the present invention, a thickened rotor vane of the type generally described hereinabove, is constructed of a plurality of independent sections or blades extending longitudinally of the assembled vane and united only at the vane ends. The individual blades may 105

be of approximately the same shape and cross-sectional area throughout their lengths and may have cross-sectional shapes substantially similar to that of the most effective portion of the assembled vane. With such a structure the liquid passages through the assembled rotor are increased to a maximum thereby permitting passage of maximum quantities of operating liquid. Each of the individual blades also presents surfaces disposed at the most efficient angle relatively to the entering liquid and to the direction of advancement of the vanes, thereby producing an assembled rotor structure of maximum efficiencies.

A clear conception of several embodiments of the invention and of the operation of devices constructed in accordance therewith, may be had by referring to the drawing accompanying and forming a part of this specification in which like reference characters designate the same or similar parts in the several views.

Fig. 1 is a transverse sectional view through the outer extremity of a vane of a hydraulic turbine rotor of the high speed low head type as constructed prior to the present invention.

Fig. 2 is a transverse sectional view through the outer extremity of a solid thickened vane of a low head high speed hydraulic turbine rotor constructed in accordance with the present invention.

Fig. 3 is a transverse sectional view through the vane of another form of low head high speed hydraulic turbine rotor embodying the present invention, the section being taken along the line III—III of Fig. 5 looking toward the hub.

Fig. 4 is a transverse sectional view through the vane illustrated in Fig. 3, the section being taken along the line IV—IV of Fig. 5 looking toward the hub.

Fig. 5 is a plan view of a low head high speed hydraulic rotor of the axial flow type, illustrating the general assemblage of a rotor embodying vanes such as illustrated in Figs. 2, 3 and 4.

While the plan view of Fig. 5 discloses a rotor having vanes each of which comprises a plurality of sections or blades extending throughout the length of the vanes, this figure will serve to illustrate the general assemblage and shape of rotors embodying vanes such as shown in Figs. 1 and 2. The rotor is of the high speed axial flow type and comprises a series of four vanes 4 of dove-tail formation, having their inner ends rigidly attached to a hub 15 and having free outer ends. The hub 15 is adapted for rigid attachment of a motion transmitting shaft which extends laterally away from the rotor in the usual manner. The area of the vanes 4 when projected upon a plane perpendicular to the axis of the rotor shaft, or as

viewed in the general direction of advancement of the operating fluid, is substantially less than the area of the annulus located between the circles which bound the inner and outer ends of the vanes. The percentage of the projected vane area with reference to the total area of the fluid passage defined by the annulus, may vary throughout a considerable range for different characteristics of the unit.

In the one piece vane 2 of the prior art illustrated in section in Fig. 1, the vane 2 is of generally dove-tail shape having varying pitch from end to end. Both the leading and trailing edges 7, 9 respectively, of this prior vane structure are relatively thin, the vane having a slightly thickened portion 5 between the edge portions 7, 9 in order to produce a vane of proper strength to resist destructive forces during operation of the rotor and in order to facilitate construction of the rotor by casting.

In the improved vane 3 a transverse cross-section of which is illustrated in Fig. 2, the vane 3 is of generally dove-tail shape and preferably has varying pitch or angularity throughout its length. The leading edge 8 of the vane 3 is relatively blunt and provides a stubby nose portion for the purpose of avoiding shock at entry of the working fluid. Receding from the edge 8, the vane 3 is of increasing thickness up to the medial portion 6 which has a maximum thickness preferably greater than one twentieth of the width of the vane 3 at the vane section illustrated, which is taken near the outer end of the vane. From the thickened medial portion 6, the vane 3 gradually tapers off toward the trailing or discharge edge 10 which may be chamfered as shown. The chamfer of the discharge edge 10 while possessing considerable novelty and utility, forms no part of the present invention.

In the improved vane 4 illustrated in section in Figs. 3 and 4, and in elevation in Fig. 5, the vane 4 is likewise of generally dove-tail shape and has varying angularity or pitch throughout its length. The sectional vane 4 is constructed of a plurality of blades 11 having working passages 12 between them, both the blades 11 and the intervening passages 12 extending longitudinally from end to end of the vane 4. In addition to having the assembled vane 4 of varying angularity or pitch throughout its length, the individual blades 11 are twisted thereby giving them varying angularity throughout their length. The inner extremities of the blades 11 are preferably rigidly attached to the hub 15 and the outer extremities of the blades 11 of each of the vanes 4, are preferably united by a strip 16 of suitable material. The assembled vane 4 is substantially similar in shape to the thickened vane 3 previously described, hav-

ing a stubby leading edge, a relatively thick medial portion and a thin chamfered trailing edge formed by a relatively thin and narrow blade 13. The contour of the assembled sectional vane 4 is represented by the light lines 14 and it will be noted that the line 14 of the vane section illustrated in Fig. 3 is substantially the same as the outline of the corresponding blade section illustrated in Fig. 2. The blades 11 may overlap as illustrated, or they may be spaced apart laterally so as not to overlap when viewed in the direction of the rotor axis.

The operation of all of the rotors illustrated herein, is generally the same, the water being admitted as an axially advancing whirling stream toward the inlet side of the rotor. As the axially advancing whirling stream of water engages the working faces of the rotor vanes, considerable of the velocity energy of the stream is converted into rotary motion appearing as torque in the main shaft which is direct connected to the rotor. The liquid delivered from the rotor retains considerable of its whirl energy, the residual whirl and velocity energy being converted into pressure energy with the aid of a decelerator or draft tube.

It has been found that thickening of the vane as illustrated in Figs. 2 and 3, produces a rotor having maximum efficiency and capable of producing maximum energy conversion without materially affecting the specific speed of the turbine. With the aid of the present improvement, specific speeds of values above 90 British system (B) or 360 metric system (M), are readily obtainable, such specific speeds being considered commercially satisfactory. Repeated tests of commercial installations embodying the thickened vanes, have proven that such a structure produces improved efficiencies over rotors of the prior art embodying thinner vanes. The thickening of the leading vane edges avoids shock at entry and also eliminates eddy losses, thus accounting to some extent for the improved results obtained. The proper formation of the leading vane faces also improves the suction or under-pressure, thereby increasing the effectiveness of the positive pressure acting on the trailing vane surfaces.

As turbines of this general type require large working passages in order to accommodate the large quantities of water necessary for efficient operation, the sectional vane construction illustrated in Figs. 3, 4 and 5 will obviously provide such desirably large working passages. Each of the individual blades 11 being of shape substantially similar to that of the assembled vanes 4, the blades will act independently of the others to effectively convert the energy of a small portion of the stream flowing through the rotor. Such a vane structure

also avoids necessity of making extreme changes in the direction or disposition of the working surfaces of the vanes, thereby maintaining most effective angles of impact.

It should be understood that it is not desired to limit the invention to the exact details of construction and of operation herein shown and described, for various modifications within the scope of the claims may occur to persons skilled in the art.

It is claimed and desired to secure by Letters Patent:

1. In a hydraulic turbine, a rotor formed to produce a specific speed of at least 90 B or 360 M, said rotor comprising a plurality of vanes radiating from a central hub, each vane having a relatively stubby inlet edge and the greatest width of each vane measured in the direction of travel thereof being less than twenty times its greatest thickness measured at the greatest vane width.

2. In a hydraulic turbine, a rotor formed to produce a specific speed of at least 90 B or 360 M, said rotor comprising more than two and less than eight dove-tail shaped vanes radiating from a central hub, each vane having a relatively stubby inlet edge and the greatest width of each vane measured in the direction of travel being less than twenty times its greatest thickness measured at the greatest vane width.

3. In a hydraulic turbine, a rotor formed to produce a specific speed of at least 90 B or 360 M, said rotor comprising a plurality of vanes having straight line generatrices radiating from a central hub and providing helical surfaces, each vane having a relatively stubby radially disposed inlet edge and the greatest width of each vane measured in the direction of travel being less than twenty times its greatest thickness measured at the greatest vane width.

4. In a hydraulic turbine, a rotor formed to produce a specific speed of at least 90 B or 360 M, said rotor comprising a plurality of nonoverlapping vanes of dove-tail shape radiating from a central hub and having free outer extremities, each vane having a relatively thick inlet edge and the greatest width of each vane measured in the direction of travel being less than twenty times its greatest thickness measured at the greatest vane width.

5. A hydraulic turbine rotor comprising a dove-tail shaped vane formed of a plurality of independent blades extending longitudinally of the vane, each of said blades having a cross-section substantially similar to that of the assembled vane.

6. A hydraulic turbine rotor comprising a dove-tail shaped vane formed of a plurality of independent blades extending longitudinally of the vane, each of said blades having a cross section substantially similar to that of the assembled vane and

the passages between said blades converging in the direction of flow of water therethrough.

7. A hydraulic turbine rotor comprising a central hub and a vane radiating from said hub, said vane being formed of a plurality of independent blades extending radially with respect to said hub, each of said blades having a cross section substantially similar to that of the assembled vane and the passages between said blades converging in the direction of flow of water therethrough.

8. A hydraulic rotor comprising a vane rotatable about an axis and having maximum width remote from said axis, said vane being formed of a plurality of blades extending longitudinally of the vane and each of said blades having substantially constant cross sectional area throughout its length.

9. A hydraulic turbine rotor comprising a plurality of dove-tail shaped vanes radiating from a central hub, each of said vanes having varying cross sectional area throughout its length and each vane being formed

of a plurality of independent blades having substantially constant cross sectional area throughout their lengths.

10. A hydraulic turbine rotor comprising a vane formed of a plurality of blades extending longitudinally of the vane and having passages between said blades converging in the direction of flow of water therethrough.

11. A hydraulic rotor comprising a vane formed of a plurality of blades extending longitudinally of the vane, each of said blades having a blunt inlet edge and having a cross section substantially similar to that of the assembled vane.

12. A hydraulic rotor comprising a plurality of non-overlapping dove-tail shaped vanes radiating from a central hub, each of said vanes being formed of a plurality of independent blades radiating from said hub and having a stubby inlet edge, the cross section of each blade being substantially similar to that of the assembled vane.

In testimony whereof, the signature of the inventor is affixed hereto.

FORREST NAGLER.
